GAS FLOW REGULATOR

Albert E. Jurs, Piedmont, Calif.

Application June 24, 1938, Serial No. 215,607

6 Claims. (Cl. 137—53)

This invention relates generally to devices for controlling flow of gases in accordance with gas pressures. More particularly the invention is concerned with devices for automatically relieving gas or vapor pressures, such as may accumulate in gas or vapor systems. Devices of this type are useful in connection with pressure receivers or storage tanks, as for example with storage tanks containing volatile liquids like gasoline or other petroleum fractions, where abnormal vapor pressure within the tank must be relieved by venting or withdrawal of gas, when it attains predetermined values.

It is an object of the invention to provide an improved device of the above character which is simple in mechanical construction, and which avoids use of conventional guide bearings for the main valve pallet or closure.

Another object of the invention is to provide a regulator or relief valve of the above character, which will have adequate provision for draining away any liquid condensate which may form within the device.

A further object of the invention is to provide a relief valve which functions for both abnormal pressures and vacuum, such as might endanger the storage tank with which the valve is used.

Another object of the invention is to provide a relief valve which will not be affected by pressure or suction surges of momentary duration.

Additional objects of the invention will appear from the following description in which the preferred embodiment of the invention has been set forth in detail in conjunction with the accompanying drawings.

Referring to the drawings:

Fig. 1 is a side elevational view, in cross-section, illustrating a regulator incorporating the present invention.

Fig. 2 is a view of the regulator illustrated in Fig. 1, partly in cross-section, the section being at right angles to the view illustrated in Fig. 1.

That form of the invention illustrated in the drawings consists of a hollow body part 10a, provided with inlet opening 11 and outlet opening 12. Where the device is used with a storage tank containing petroleum fractions, the outlet 12 may connect to a vapor recovery system, or may discharge directly to the atmosphere. Within the valve body there is a main valve pallet or closure 13. Closure 13 cooperates with a stationary seat ring 14, which in turn is carried by the raised annular flange 16. The lower face of the closure 13, which contacts with the

upper face of seat ring 14, can be faced with a removable ring 17 of suitable material such as Duprene, Corpren, or like resilient synthetic rubber. As the device is normally used seat ring 14 is in horizontal position, so that the closure 13 moves vertically between open and closed positions.

In the embodiment illustrated the closure 13 is formed of suitable rigid metal, as for example cast metal or metal alloy, and its central portion is dished downwardly. Threaded into the lower end of the closure 13 there is a short pipe section 18, which forms a restricted orifice 19. This orifice establishes restricted communication between the upper and lower sides of the closure 13, for the purpose to be presently explained. Also any condensate formed or draining down upon the upper face of closure 13 is drained through orifice 19 into the inlet opening 11.

In conjunction with the closure 13 there is an annular flexible diaphragm 21. This diaphragm is formed of suitable flexible material such as fabric reinforced synthetic rubber. The inner peripheral edge portion of the diaphragm 21 is clamped and sealed to the outer peripheral portion of the closure 13 as illustrated. The outer peripheral edge portion of the diaphragm 21 is clamped between the main body portion 10a and the intermediate body portion 10b. When the closure 13 is in closed position as illustrated in Fig. 1, there is no appreciable sag to the diaphragm 21, and the diaphragm serves to generally center the closure with respect to the valve seat.

While the centering thus afforded by diaphragm 21 can be relied upon in the absence of additional centering or guiding means, it is desirable to use additional means to insure against the cocking or chattering. Thus a depending rod 23 is shown attached to the center of the closure 13, and the lower end of this rod is attached to a plurality of radially extending strips 24. These strips are formed of suitable flexible material, such as fabric reinforced synthetic rubber, and the outer ends of these strips are attached to the adjacent portions of the body 10a, as indicated at 26. It will be noted as viewed in Fig. 2 that strips 24 are drawn substantially taut when the valve member 13 is in closed position.

The intermediate body part 10b affords a closure wall 27 extending over the valve member 13 and the annular diaphragm 21. Thus there is formed a closed chamber 28 which is in com-

munication with the inflow opening 11 through the orifice 19. Assuming a relatively fixed pressure upon the outflow side, as for example atmospheric pressure, a pressure somewhat greater than atmospheric upon the inflow side will also exist in chamber 28, because of equalizing flow through orifice 19. Such pressure in chamber 28 acts upon diaphragm 21 and closure or pallet 13, to retain the pallet closed upon its seat. 5
10 Opening of the closure or pallet 13 is accomplished by rapid venting of chamber 28, whereby pressure acting upon the lower side of the pallet is sufficient to force it upwardly to open position. In the type of valve illustrated the venting is controlled by pilot valve means, which in turn acts in response to the pressure upon the inflow side.

The desirable type of pilot valve means illustrated is constructed as follows: Bolted upon 20 the intermediate body part 10b, there is an upper body part 10c. Between these body parts and particularly above the wall 27, there is a diaphragm assembly 29. This assembly includes a rigid disc 31, and an outer flexible diaphragm 25 portion 32. The flexible portion 32 has its outer peripheral edge clamped between annular flanges, afforded by the body parts 10b and 10c. The closed gas chamber 30 below the diaphragm 32, is adapted to be connected to the 30 source of pressure on the inflow side of the regulator, as for example to the vapor space of the tank with which the device is used, as by means of a pipe 33. Note that wall 27 forming the lower wall of chamber 30, is sloped as illustrated in Fig. 2, and that the duct 34 leading to pipe 33 is also sloped, whereby any condensate tending to accumulate within chamber 30 is drained back through pipe 33. The space 35 above diaphragm 32 is in communication with 40 the atmosphere, as by means of one or more openings 40.

The disc 31 of diaphragm assembly 29, is attached to the lower end of a rod 36. The upper end of rod 36 exterior of the body, has a 45 pivotal connection 37 with a lever 38. This lever has a pivotal connection 39 with the fixed supporting brackets 41 and 42. The adjacent end 43 of lever 38 operates within a fork 44, carried by bracket 41, in order that the lever 50 may be steadied. The extended end of lever 38 carries the adjustable weight 46.

The pilot or venting valve which is controlled by movements of rod 36, includes a pair of concentric stationary seat rings 47 and 48. A valve 55 disc 49 is disposed above the seat rings 47 and 48, and the lower side of this disc is provided with a suitable facing 51, such as a facing made of resilient synthetic rubber. Disc 49 is attached to the lower end of an annular shell 60 52, the upper end of which is provided with an inwardly extending flange 53, for engagement with an annular shoulder 54 formed on a sleeve 56. Sleeve 56 is attached to the upper end of rod 36, and is loosely accommodated within the shell 52. Valve disc 49 also loosely fits about the rod 36, and interposed between disc 49 and the lower end of sleeve 56, there is a compression spring 57. The annular space 59 which communicates through the concentric seats 47 and 65 48, is connected by passages 61, with the chamber 28 above the pallet 13. Therefore when valve disc 49 is moved to open position by upward movement of rod 36, chamber 28 is directly vented to the atmosphere through 70 75 sages 61.

Movement of the rod 36 and the diaphragm assembly, can be limited by a suitable means. Thus the lower end 62 of rod 36 engages a pad 63, formed centrally of wall 27, to limit downward movement of rod 36. Upward movement 5 of rod 36 is limited by an adjustable set screw 64, shown carried by bracket 41, and which is adapted to engage the end portion 43 of lever 38.

Operation of the regulator described above, 10 can be outlined as follows: It will be assumed that the inlet opening 11 is connected to a storage tank containing a volatile petroleum fraction and to which pipe 33 is also connected. The outlet opening 12 can be at atmospheric 15 pressure, and the device is set by adjusting weight 46, to remain closed until the pressure in the tank has increased beyond a predetermined value above atmospheric.

For pressure values below the maximum value 20 for which the device is set, pallet 13 will remain closed upon the seat 14, since the pressure in chamber 30 is the same as the inlet pressure, while the combined area of the pallet 13 and the diaphragm 21 exposed to gas in 25 chamber 28 is considerably greater than the area of the pallet which is exposed to the inflow pressure in opening 11. When the pressure in the tank increases beyond the predetermined 30 value for which the device is set, the pressure within chamber 30, forces the diaphragm 32 upwardly, and the raising of rod 36 against weight 46 moves the pilot valve disc 49 to open position. Thus the chamber 28 above the pilot 13 35 is freely vented through passages 61, and the reduction in pressure in chamber 28 causes the upward forces acting upon pallet 13 to move it to open position. Thus gases or vapors within the tank are permitted to escape through the outflow opening 12. When the pressure within 40 the tank falls below the pressure value for which the device is set, diaphragm assembly 29 moves downwardly under the urge of weight 46, and pilot valve disc 49 is forced down upon its seat by the compression spring 57. Pressure rapidly 45 builds up in chamber 28 by virtue of a flow of gas from the inflow opening 11 through the restricted orifice 19. Within a short time sufficient pressure is built up in chamber 28 to force the pallet 13 to closed position. 50

Because of the manner in which the pallet 13 in effect forms a continuation of the pressure surfaces formed by diaphragm 21, the device is also opened when conditions of sufficient vacuum are experienced within the tank. This is because when the pressure in chamber 28 has been lowered below a given degree of vacuum such as is unsafe for the tank, the upward pressure of the atmosphere on the lower side of diaphragm 21 lifts the 55 pallet to open position. 60

In some instances it is desirable to afford means whereby a sudden condition of vacuum in the tank is immediately applied to chamber 28 to cause immediate opening of the pallet. This can be accomplished by a check valve 65, interposed between the passage 34, and the chamber 28. This check valve can be of simple construction, consisting for example of a sleeve 66, the upper edge of which forms a valve seat to cooperate 70 with the movable disc 67. Disc 67 is loosely retained in place by means of the central screw 68, and if desired a light compression spring 69 can be provided to urge the disc 67 towards closed position. The openings through this check should 75

afford a cross sectional flow area substantially greater than orifice 19. In the event a condition of unsafe vacuum is suddenly experienced within the storage tank, check valve 65 is immediately opened because of the greater pressure in chamber 28, which must necessarily exist at that time because of insufficient time afforded for equalizing of pressures above and below the pallet 13. Such application of vacuum to chamber 28 will cause immediate opening, because of the pressure of the atmosphere upon the lower side of the flexible diaphragm 21.

As pointed out above the check valve 65 takes care of sudden conditions of unsafe vacuum in the storage tank, to cause immediate opening of the pallet 13. As previously explained where the conditions of unsafe vacuum within the storage tank are attained gradually, the pallet 13 also opens automatically to permit inflow of gas from the outflow opening 12 because of the reduction in pressure in the gas chamber afforded by orifice 18.

Check 65 also performs an added function in that it insures venting of chamber 28 to the atmosphere in the event diaphragm 32 is ruptured. With a small pressure pipe 33, venting through check 65 to the atmosphere, and through the ruptured diaphragm, can occur at a rate sufficient to cause opening of the pallet, thus preventing undue building up of vapor pressure in the tank under such conditions.

It will be evident from the foregoing that my regulator is of simple construction, and is designed to avoid troublesome machined guide bearings, which are subject to corrosion and jamming and which tend to interfere with reliable operation. The making of the pallet 13 to serve both the function of a closure for the main valve seat and also as a part of the fluid pressure operated assembly, makes for simplicity and reliability of operation. Also this arrangement together with the dished form of the pallet 13, insures drainage of condensate with return of this condensate directly to the inflow opening 11. With the preferred construction illustrated, I not only take into account conditions of extreme pressure, but also conditions of vacuum which may injure the storage tank. As previously pointed out both conditions of unsafe pressure and vacuum are relieved, by opening of the pallet 13, and in addition the vapor tank is protected in the event the device is made inoperative by rupture of the pilot diaphragm.

I claim:

1. In a gas flow regulator, a body having inflow and outflow openings, the inflow opening being adapted to be connected to a source of gas or vapor normally under pressure, an annular seat formed within the body, a closure pallet cooperating with said seat and formed of rigid material, said pallet being dished downwardly and having its lower portion provided with a flow restricting orifice for establishing restricted communication between the upper and lower sides of the pallet, and a flexible annular diaphragm, the inner peripheral edge of said diaphragm being attached to the outer edge portion of the pallet and the outer peripheral edge portion of the diaphragm being attached to the body, said body being formed whereby the lower side of said flexible diaphragm is freely exposed to gas pressure upon the outflow side of the regulator and being also formed to afford a closed gas chamber extending over both the diaphragm and the pallet,

said gas chamber being adapted to be vented with said orifice open to effect opening of the pallet.

2. In a gas flow regulator, a body having inflow and outflow openings, the inflow opening being adapted to be connected with a source of gas or vapor normally under pressure, a substantially horizontally disposed valve seat formed within the body, a substantially rigid closure pallet cooperating with said valve seat, said pallet being dished downwardly, means forming a flow restricting orifice extending directly through said pallet and disposed near the lower end of the same, said orifice serving to drain liquid condensate into the inflow opening, an annular flexible diaphragm having its inner peripheral edge portion attached to the outer peripheral edge portion of the pallet, said diaphragm having its outer peripheral edge portion attached to said body, and serving to retain the pallet centered with respect to the seat, said body being formed to freely expose the lower side of said diaphragm to outflow pressure and being also formed to provide a closed gas chamber extending over both the upper side of the diaphragm and the upper side of said pallet, whereby movement of said pallet is controlled solely in response to gas pressure exerted thereon and on said diaphragm, said closed chamber being adapted to be vented with said orifice open to effect opening of the pallet.

3. In a gas flow regulator, a body having inflow and outflow openings, the inflow opening being adapted to be connected to a source of gas or vapor normally under pressure, a substantially horizontal valve seat formed within the body, a substantially rigid closure pallet cooperating with said valve seat, means for establishing communication between the upper and lower sides of said pallet, said last means including a flow restricting orifice extending through the pallet and also a check valve for controlling flow between the two sides of the pallet, said check valve being opened by gas pressure below the pallet, and an annular flexible diaphragm having its inner peripheral edge portion attached to the outer peripheral edge portion of the pallet and having its outer peripheral edge portion attached to the body, said body being formed whereby the lower side of said diaphragm is freely exposed to outflow pressure and whereby a closed gas chamber is formed extending over both the upper side of the diaphragm and the upper side of the pallet, said gas chamber being adapted to be vented to effect opening of the pallet.

4. In a gas flow regulator, a body having inflow and outflow openings, a valve seat formed within the body, a movable closure cooperating with said valve seat, means for effecting automatic opening movement of said valve member, said means including a gas chamber adapted to be vented, means for establishing a connection between the source of gas or vapor pressure and said chamber, and means for effecting venting of said gas chamber responsive to either a condition of excess pressure or extreme vacuum from said source.

5. In a gas flow regulator, a body having inflow and outflow openings, the inflow opening being adapted to be connected to a source of gas or vapor normally under pressure, an annular seat formed within the body, the passage through said seat serving to establish communication between the inflow and outflow sides of the regulator, a closure pallet having an annular surface cooperating with said seat, said pallet being formed of rigid material and having an outer peripheral

edge portion extending beyond said annular seat, an annular flexible diaphragm having its inner peripheral edge portion attached to the outer peripheral edge portion of the pallet in a plane parallel to and adjacent the plane of said annular surface, the outer peripheral edge portion of the diaphragm being attached to the body, said body being formed whereby the lower side of said flexible diaphragm is freely exposed to gas pressure upon the outflow side of the regulator and being also formed to provide a closed chamber extending over both the flexible diaphragm and the pallet, whereby movement of said pallet is controlled solely in response to gas pressure exerted thereon and on said diaphragm, means establishing restricted communication between said chamber and the inflow side of the regulator, said chamber being adapted to be vented with said communication establishing means open to effect opening of the closure pallet, and means in addition to said annular diaphragm, attached to said pallet, and serving to minimize lateral cocking of the same.

6. In a gas flow regulator, a body affording inlet and outlet openings, an annular valve seat formed in the body, an annular pallet disposed upon the valve seat and having an annular surface adapted to seat upon the seat, an annular flexible diaphragm having its inner peripheral edge attached to the outer periphery of the pallet in a plane parallel to and adjacent the plane of said annular surface, the outer peripheral edge portion of the diaphragm being attached to the body, means forming a closed gas chamber over the diaphragm and pallet, means forming a continuous restricted communication between the inlet and said chamber whereby inlet pressure in said chamber normally serves as substantially the entire force on the diaphragm to retain said pallet closed upon the seat, and means for rapidly venting gas from said chamber to effect opening of said pallet, said pallet being also opened by vacuum beyond a predetermined degree in said chamber due to a corresponding vacuum in the inlet.

ALBERT E. JURS.
